(57) **CLAIM**

The ornamental design for a light fixture, as shown and described.

DESCRIPTION

FIG. 1 is a top perspective view of the new design for a light fixture.

FIG. 2 is a right side elevation view thereof, which is a mirror image of the left side elevation view thereof;

FIG. 3 is an edge elevation view thereof;

FIG. 4 is a top plan view thereof; and

FIG. 5 is a bottom plan view thereof.

FIG. 6 is a top perspective view of second embodiment of the new design for a light fixture wherein all features are the same as the first embodiment, the only difference being the transparent quality of the planar section thereof; and,

FIG. 7 is a top perspective view of third embodiment of the new design for a light fixture wherein all features are the same as the second embodiment, the only difference being the addition of a second identical module.

The broken lines shown on the drawings represent portions of the light fixture that form no part of the claimed design.
